POWER HAMMER

Howard F. Caudill, Lutz, Fla., assignor to C. L. Guild Construction Co., Inc., a corporation of Rhode Island

Filed July 7, 1959, Ser. No. 825,496

3 Claims. (Cl. 121—30)

This invention relates broadly to power hammers and more particularly to that general category of hammers which operate by means of fluid pressure such as steam or compressed air. Within this general category of power hammers, there are two distinct types. The first type is what is known as a single-acting hammer, which utilizes the motive fluid on the upstroke of the piston to raise the ram and thereafter exhausts the motive fluid to permit the piston and the ram to fall by gravity and strike a blow due to the acceleration of gravity alone acting upon the ram. Such a hammer has a measured stroke or free fall of a known weight, whereby the driving energy can be accurately determined, inasmuch as slight variations of the motive fluid pressure do not affect the power of the blow. The second type of hammer, known as a double-acting hammer, not only utilizes the pressure of the motive fluid against the piston to raise the ram, but also uses this pressure to accelerate the ram on the down stroke. In this type of hammer a relatively light weight ram coupled with a relatively short stroke will develop about three to four times the driving energy of a similarly sized single-acting hammer. However, this type of hammer has the disadvantage of depending upon the pressure of the motive fluid and therefore the driving power of such a hammer may not necessarily be constant. Accordingly, a double-acting hammer is not to be preferred where exact driving energy is desired. It is apparent, therefore, that a hammer selection must be made for each type of job.

This invention is designed with a view of obviating the necessity of using two distinct types of hammers and is characterized by providing a power hammer with optional operation; that is, the hammer may operate as a single-acting hammer where exact driving energy is required as in driving foundation piling to a known bearing capacity or as a double-acting hammer where increased driving power is advantageous in driving such items as steel sheet piling and the like.

It is therefore the principal object of this invention to provide a construction of a power hammer which may be readily changed so as to operate either as a single-acting hammer or as a double-acting hammer.

Another object of the invention is to provide a simple means for controlling the distribution of the motive fluid into the piston cavity.

A further object of the invention is the provision of a power hammer which may be alternately operated either as a single- or a double-acting hammer and in which the parts comprising the changeover assembly are held at a minimum.

With these and other objects in view, the invention consists of certain novel features of construction as will be more fully described and particularly pointed out in the appended claims.

In the drawings:

Figure 1 is a vertical sectional view taken substantially centrally through the hammer which is constructed in accordance with the invention;

Figure 2 is a sectional view taken substantially on lines 2—2 of Fig. 1 showing the arrangement of the valve intake and exit ports; and

Figure 3 is a vertical sectional view on an enlarged scale showing the valve block assembly and taken substantially on lines 3—3 of Fig. 2.

Referring now to the drawings for a more detailed description of the various parts of the device, there is shown in Fig. 1 a power hammer having a suitable housing which is in the form of an upper cylinder 11 and a lower cylinder 12. Between the two cylinders 11 and 12 is a valve block 13 and at the upper end of cylinder 11 is a cylinder head assembly 14, while at the lower end of cylinder 12 is a retaining ring 15. These two cylinders and the valve assembly are held together in operative arrangement between the head 14 and the ring 15 by a plurality of tie rods 16 which tie rods are provided with suitable threaded ends and nuts as at 17. Disposed within the upper cylinder 11 is a piston 18 which piston is provided with one or more piston rings 19 suitably disposed within grooves in a manner known to those mechanics skilled in the art. Attached to and extending from the piston 18 is a piston rod 20 that passes through a bore 21 in the valve block 13 and has threadingly attached at its lower end a ram 22. Disposed in suitable grooves in the periphery of the ram 22 are one or more piston rings 23 which provide sealing engagement with the interior bore of the lower cylinder 12. Located at the lower end of the cylinder 12 is an anvil block 24 which has a reduced diameter section as at 25 which is received within the retaining ring 15.

Motive fluid for operating the power hammer may be supplied by means of an inlet pipe connection 26 which is located on a boss 27 forming a part of the valve block 13. This connection 26 communicates with a horizontal passage 28 and a vertical passage 29. Passage 28 communicates with an upper valve chamber 30 while the passage 29 communicates with a lower valve chamber 31. Disposed within each of the valve chambers 30 and 31 are valve plugs 32 and 33 respectively, which plugs are generally cylindrical to fit within the generally cylindrical chambers 30 and 31 and are provided with a plurality of axial bores 34 and 35 respectively. The two valve plugs 32 and 33 are joined together for simultaneous action by a valve stem 36 which stem extends outwardly of the valve chambers 30 and 31 a substantial distance for a purpose which will presently appear. The valve chambers 30 and 31 open into the upper and lower cylinders 11 and 12 respectively and have communicating therewith exhaust ports 37, 38 respectively. Disposed at the lower end of the vertical passageway 29 is a control valve cock 40 which is provided with a stem 41 that is adapted to rotate in a suitable packing means 42, rotating being imparted by virtue of the nut 43 at the end of the stem 41. In the position shown in the drawings, this cock is shown as closing off an outlet port 44 so that thru communication is had from the passageway 29 through port 29A into the valve chamber 31.

As viewed in the drawings, in Fig. 1 the hammer is midway of its stroke, while in Fig. 3 the hammer is at the end of its downward stroke at which location the bottom face of the piston 18 is in contact with the upper end of valve stem 36. This causes the valve assembly consisting of the stem and two valve plugs 32 and 33 to be pushed downwardly to a point where the inlet pipe connection 26 is in communication with the upper cylinder 11 through passageway 28. Additionally, the exhaust port 37 is closed, the intake port 29A is closed, and the exhaust port 38 is open leaving communication from the lower cylinder to the exhaust port 38 through the bores 35 of the valve plug 33. Accordingly, as the pressure from the motive fluid enters the upper cylinder 11 below

the piston head 18, the piston head and the ram 22 are moved upwardly within the respective cylinders until the top face of the ram 22 contacts the lower end of the valve stem 36. When this occurs, the ram will push the valve plugs upwardly as viewed in the drawing to a point where the intake passageway 28 is closed, the exhaust port 37 is opened, the intake port 29A is opened and the exhaust port 38 is closed. The pressure from the motive fluid then enters the lower cylinder 12 forcing the ram downwardly to the end of its stroke where it strikes the anvil block 24 and delivers its driving energy to the object being driven. This then completes one stroke of the hammer when the hammer is arranged for operating as a double-acting power hammer.

To change the power hammer from a double-acting to a single-acting operation, it is necessary only to turn the control cock 40 by rotating it via the means 43 180°. This then orients the cock in such a way that it closes off the passageway 29 as shown by the broken line at 40° and afford communication from the valve chamber 31 through the port 29A to the exhaust port 44. The valve assembly operates in exactly the same manner as previously described except that when the piston 18 reaches the top of its stroke and the ram 22 pushes the valve rod 36 upwardly thereby closing off communication between the upper cylinder 11 and the passageway 28, the lower cylinder will then be opened to the atmosphere via exhaust port 44 and allow the lower cylinder to take in air on the downward stroke, thus avoiding a tendency to form a vacuum in the lower cylinder 12 as the ram 22 descends.

It will be apparent that there is disclosed a power hammer which may readily be operated either as a single-acting or a double-acting device merely by a simple rotation of a valve cock. The entire valve assembly is extremely simple in construction and while in the foregoing description there has been eliminated many details of actual construction of the entire device, it suffices to say that suitable means are provided through the bore 21 of the valve body 13 to prevent leakage of motive fluid pressure from the upper cylinder to the lower cylinder or vice versa. Further, it should be appreciated that the valve plugs 32 and 33 are in a close sliding fit with the walls of the valve chambers 30 and 31 and of course if preferred, suitable sealing means between the valve plug and the valve chamber walls may be provided. No particular packing is necessary around the valve stem 36 between the chambers 30 and 31 for any leakage therebetween is not detrimental to the operation of the device. It should be particularly noted in connection with the valve assembly that no means are shown to maintain the valve plugs in their driven position. This is due to the fact that the pressure of the motive fluid arriving through the appropriate intake port is sufficient to maintain the valve plugs in position during the necessary travel of the piston 18 between its extreme positions. If, of

course, under certain conditions such an arrangement does not prove feasible such as extremely adverse operating conditions, then suitable means well known to those skilled in the art can be utilized to provide a positive stop for the valve plugs at each end of their travel, which stop means will retain the valve plugs in the desired position.

It should be pointed out further that the power hammer disclosed is capable of working as a single-acting hammer at any angular orientation sufficiently above a horizontal so that the ram will fall under the influence of gravity, and of course, will work as a double-acting hammer in any position. Further, such a hammer is capable of operating under water, it merely being necessary to modify the lower end of the hammer at the anvil portion to prevent water entering at this particular location surrounding the anvil block.

I claim:

1. In a pile driving hammer having an upper cylinder 20 and a lower cylinder, a valve block disposed between said cylinders and a piston disposed in said upper cylinder with a piston rod connected thereto and passing through said valve block into said lower cylinder and attached to a ram valve means for supplying motive fluid comprising two valve chambers located within said valve block, one of said chambers communicating with said upper cylinder, the other of said chambers communicating with said lower cylinder, valve plug means disposed within each valve chamber, a pair of passageways for supplying motive fluid to each valve chamber, means located within one of said passageways to close off said passageway and simultaneously vent the associated valve chamber whereby by the operation of said last named means the hammer may be changed from a double-acting hammer to a single-acting hammer.
2. In a hammer as in claim 1 wherein exhaust ports are disposed within each of said valve chambers and said valve plugs have a plurality of passageways therethrough, means for operating said valve plugs in unison so that when one valve chamber is closed, the other valve chamber will be opened.
3. In a hammer as in claim 1 wherein the said one passageway has an exhaust port and the means located within the one of said passageways normally closes the exhaust port within said passageway and upon operation closes off said passageway opening the valve chamber in communication therewith to said exhaust port.
